Primary Examiner—Cathron Brooks*Assistant Examiner*—Deanna Fluegeman*(74) Attorney, Agent, or Firm*—Woodcock Washburn LLP(57) **CLAIM**

The ornamental design for a reader plate, as shown and described.

DESCRIPTION

FIG. 1 is a front perspective view of a reader plate showing our new design;

FIG. 2 is a front plan view thereof;

FIG. 3 is a side elevational view thereof;

FIG. 4 is a bottom elevational view thereof;

FIG. 5 is a top elevational view thereof; and,

FIG. 6 is a back plan view thereof.

The broken lines define the bounds of the claimed design in the present application, and form no part thereof.
